(57) **CLAIM**

The ornamental design for a surface configuration of forklift, toy, and/or other replicas, as shown and described.

DESCRIPTION

This application is related to the following co-pending applications:

Application Serial No. 29/262,038, entitled “Surface Configuration of a of a Forklift, Toy, and/or Other Replicas;” and Application Serial No. 29/262,037, entitled “Surface Configuration of a Forklift, Toy, and/or Other Replicas.”

FIG. 1 is a right side view of a first embodiment of a surface configuration of forklift, toy, and/or other replicas according to my novel design;

FIG. 2 is a left side view thereof;

FIG. 3 is a rear view thereof; and

FIG. 4 is a front view thereof.

FIG. 5 is a right side view of a second embodiment of the surface configuration of forklift, toy, and/or other replicas according to my novel design;

FIG. 6 is a left side view thereof;

FIG. 7 is a rear view thereof; and

FIG. 8 is a front view thereof.

FIG. 9 is a right side view of a third embodiment of the surface configuration of forklift, toy, and/or other replicas according to my novel design;

FIG. 10 is a left side view thereof;

FIG. 11 is a rear view thereof; and,

FIG. 12 is a front view thereof.
